UNITED STATES PATENT OFFICE.

ZALMON B. WAKEMAN, OF CHICAGO, ILLINOIS, ASSIGNOR OF ONE-HALF TO
MAURICE R. BORTREE, OF SAME PLACE.

RAZOR-STROP.

SPECIFICATION forming part of Letters Patent No. 307,821, dated November 11, 1884.

Application filed October 17, 1883. (No model.)

To all whom it may concern:

Be it known that I, ZALMON B. WAKEMAN, a citizen of the United States, and residing at Chicago, in the county of Cook and State of Illinois, have invented a certain new and useful Improvement in Razor-Strops, which is fully set forth in the following specification, reference being had to the accompanying drawings, in which—

10 Figure 1 represents a side elevation of my improved razor-strop, with a portion of the handle cut away; Fig. 2, a longitudinal section taken at the line $x\ x$, Fig. 1; Fig. 3, an end view of the handle; Fig. 4, a transverse 15 section taken at the line $y\ y$, Fig. 1; Fig. 5, a longitudinal section of a portion of the strop, taken on the line $x\ x$, Fig. 1, enlarged from the view shown in Fig. 2. Fig. 6 is a longitudinal section of a modified form of my strop, 20 showing one side thereof made flexible. Fig. 7 is a transverse sectional view taken at the line $z\ z$ in Fig. 6; and Fig. 8 is a plan view of one end of the strop shown in Fig. 6, with the loose straps thrown back, so as to show the 25 fastening of the flexible plate to the wooden part of the strop.

All razors are made thin, having concave sides, the backs of the razors being thick. When the razors are sharpened upon either a 30 flat surface or a surface that yields, so that the strop becomes concave in its contour, the surface of the strop passes across the edge and soon destroys it.

The object of my invention is to have a convex surface upon which a razor is stropped, the convexity of the surface of the strop being adapted to conform to the concave form of the side of the razor. I make this convex surface of the strop flexible, so as to be slightly yielding, and so as to adapt it to receive the desired convexity, according to the shape of the 40 razor.

My invention consists in a convex flexible razor-strop, and in the special combinations 45 and features shown, and hereinafter fully described.

In the accompanying drawings, A represents a flexible metallic plate, one end of which is attached to the handle B of the strop.

50 C is a leather or other equivalent, which cov-

ers the flexible metallic plate A, and which is intended to have a surface suitable for sharpening the razor.

D are straps, of leather or equivalent material, secured at one end, as at E, to the razor-strop, and can be laid over a convex surface of the strop, so that the strop can have two or more surfaces of different character, each of which is used as required, according to the condition of the razor.

G is a rod attached to one end of the strop, as shown, and also is attached to the movable piece H, which passes through the handle of the strop, and can be secured at the desired place on the handle by means of notches I, or other equivalent appliances. By pulling the sliding piece H the flexible plates A are given a greater convexity, and by securing the sliding piece H by the notches I at the desired position they are caused to retain the convexity given them, thereby making a more or less convex surface on which the razor is sharpened. The leathers C and D, that are laid over the convex surfaces of the plate A, receive the same convexity, and thereby make a surface 75 on which the razors are sharpened.

J is a loop or its equivalent for hanging the razor-strop upon a hook, so that the strop can be used by barbers and others in the same manner that they use leather straps for sharpening the razors; but the straps used in connection with my strop are given the convex surface to lie upon, so that the razor is sharpened upon a better convex surface.

I can use my strop by giving one of the 85 plates its convexity by means of a spring, K, of the form shown in Fig. 6. One portion, L, of the strop therein shown is made of wood or other equivalent material. To this rigid piece L is secured the flexible plate A. It is secured 90 at one end by means of the screw M, which passes through a slot in said plate, allowing the plate to slide longitudinally on said screw to receive greater or less convexity. The spring K rests against the rigid piece L, and 95 is secured in place by means of the pieces N, under which its ends pass in such manner that it can slide thereunder and become more or less compressed. It can also be removed laterally from said pieces N, leaving the flexi- 100

ble plate A unsupported at its center by the spring.

O is a convex hone, rigid and having an oval surface from side to side, as clearly shown 5 in Fig. 7. I secure this convex hone O to the rigid piece L of the strop, substantially as shown in Fig. 6. This hone is intended to have a rigid surface upon which the razor can be honed, as well as otherwise sharpened, upon 10 a convex surface adapted to fit the concave shape of the razor-blade.

My razor-strop, when intended for use by barbers, need have but one flexible metallic plate A, with a suitable connecting-rod, G, or 15 its equivalent, to bend it into its desired convex form, as one flexible convex surface might be sufficient when the strop is suspended from a hook by means of the loop J or its equivalent.

20 P are wire loops for connecting the extra straps D to one end of the razor-strop, and are connected in such way that these straps may be thrown back when desired to sharpen the razor upon the surfaces of the straps C, that are attached rigidly to the surface of the flexible plates A.

Q is a rivet passing through the ends of the flexible plates A and the strap C, and R is a rivet passing through the other ends of the 30 same and the handle, so as to secure them to the handle B.

S is a plate attached to the end of the handle, with a hole in it for the sliding piece H, and a cross-piece, T, with which the notches 35 I of the sliding plate H engage to hold the sliding piece at any desired position to give the flexible plates A their desired convexity. Other equivalent forms may be used for that purpose. The connecting-rod G is made elliptical, as shown by dotted lines in Fig. 1, and 40 is made of spring-wire, so that when the strop is drawn into position for use, with its elastic plates A made convex, this connecting-rod G will yield, making the convex surfaces of the 45 strop elastic by means of this connecting-rod, consisting of a spring. The rod G serves a

double purpose, one purpose being to draw the flexible pieces A into their desired convexity, and the other purpose is to give the surfaces a flexibility on account of the connecting-rod G springing and allowing the strop to extend slightly under pressure against the convex surfaces. 50

Having thus fully described the construction and operation of my invention, what I claim as 55 new, and desire to secure by Letters Patent, is—

1. The combination, in a razor-strop, of the two flexible plates A, having opposite convex surfaces, flexible coverings or surfaces adapted 60 for sharpening razors, and a suitable mechanism for adjusting said flexible plates to give them different degrees of convexity, substantially as specified and shown.

2. The combination of the two flexible plates 65 A, the flexible covering-surfaces C, the rod G, attached to one end of the flexible plates A, and extending between them, and the sliding plate H, attached to said rod and connected to the handle of the strop, and mechanisms for holding 70 the sliding rod H in the position to which it is adjusted, all combined and operating substantially as specified and shown.

3. The combination, in a razor-strop, of one or more flexible plates, A, the double spring- 75 rod G, and suitable mechanism connecting the spring-rod with the handle of the strop, for giving the strop its suitable convexity, the spring-rod G being adapted to yield and admit of the convex strop surface or surfaces 80 yielding as it is used, as specified and shown.

4. The combination, in a razor-strop, of the sliding piece H, plate S, handle B, and suitable means for connecting both sliding piece and handle to the flexible plates A, to give 85 them the desired convexity, substantially as specified and shown.

ZALMON B. WAKEMAN.
